[57] **CLAIM**

The ornamental design of a housing for a telephone, substantially as shown and described.

DESCRIPTION

FIG. 1 is a perspective view of a housing for a telephone embodying our new design;
FIG. 2 is a top plan view thereof;
FIG. 3 is a bottom plan view thereof;
FIG. 4 is a side view thereof, the opposite side being essentially a mirror image of the one shown;
FIG. 5 is a right end view of FIG. 4; and
FIG. 6 is a left end view of FIG. 4.

FIG. 1

FIG. 2

FIG. 3

FIG. 4

FIG. 6

FIG. 5
